M. C. WATERS

SWITCH

Filed April 22, 1921

Inventor

M. C. Waters.

By

Lacy & Lacy, Attorneys

UNITED STATES PATENT OFFICE.

MARION C. WATERS, OF BROOKFIELD, MISSOURI.

SWITCH.

Application filed April 22, 1921. Serial No. 463,442.

To all whom it may concern:

Be it known that I, MARION C. WATERS, a citizen of the United States, residing at Brookfield, in the county of Linn and State 5 of Missouri, have invented certain new and useful Improvements in Switches, of which the following is a specification.

This invention relates to an improved switch particularly designed for use in connection with motor vehicle transmissions and seeks to provide a device which may be readily attached to a transmission gear case and wherein, when the reverse gear of the transmission is shifted to active position, the 15 switch will be closed.

Other and incidental objects will appear hereinafter.

In the accompanying drawings:

Figure 1 is a sectional view showing my 20 improved switch attached to the gear case of a conventional transmission.

Figure 2 is a side elevation illustrating a slight modification of the invention.

Referring now more particularly to the 25 drawings, I have, for convenience, shown my improved switch in connection with a conventional transmission including a gear case 11. One of the shifter rods of the transmission is indicated at 13, and one of the shifter 30 forks at 14, the fork being movable rearwardly along the rod for shifting the reverse gear of the transmission to active position.

In carrying the invention into effect, I employ a tubular switch casing 18 which, as 35 shown in Figure 2, is threaded at one end through the rear end wall of the gear case 11. This casing is preferably formed of metal and slidably therein is a plunger 19 having a body snugly but freely fitting 40 within the casing. Projecting from one end of the plunger body axially thereof is a switch contact rod 20 and projecting from the plunger body at its opposite end is a somewhat shorter rod 21 alining with the 45 rod 20 and extending forwardly into the gear case 11 in the path of rearward movement of the shifter fork 14. Threaded into the inner end of the switch casing is a closure plug 22 slidably receiving the rod 21 50 of the plunger therethrough and threaded into the casing at its outer end is a cupped dielectric closure plug 23. Bearing between the plug 23 and the body of the plunger is a spring 24 normally holding the plunger 55 body retracted in engagement with the plug 22. Extending through the plug 23 axially

thereof is a binding post 25 secured by a nut 26 and mounted upon the inner end of the post within the skirt of the plug is a substantially U-shaped switch member having 60 confronting resilient switch fingers 27. Threaded upon the outer end portion of the post to confront the nut 26 is a binding nut 28. As suggested in the drawings, a circuit wire, as conventionally illustrated at 65 31, is connected to the binding post 25.

As will now be readily understood in view of the preceding description, when the shifter fork 14 is moved rearwardly for shifting the reverse gear of the transmission 70 to active position, said fork will engage the rod 21 of the plunger 19 and move the plunger within the switch casing 18 to engage the switch contact rod 20 between the switch fingers 27 for closing the switch. On 75 the other hand, when the shifter fork 14 is then subsequently moved forwardly for shifting the reverse gear of the transmission to neutral position, as shown in Figure 2, the plunger 19 will be freed. Accordingly, 80 the spring 24 will act to immediately retract the plunger and open the switch.

In Figure 2 of the drawings, I have illustrated a slight modification of the invention. 85 Transmissions of some designs employ longitudinally movable shifter rods instead of stationary rods and movable shifter forks, as illustrated in connection with the preferred construction. The modification of Figure 2 is accordingly designed to adapt 90 the device for use in connection with a gear set wherein the shifter rods themselves are movable. In Figure 2, a conventional gear case is indicated at 32 and one of the shifter rods at 33, this rod being movable rearwardly through the gear case for shifting the reverse gear of the gear set to active position. Bolted or otherwise secured at one end to the rear end wall of the gear case is a bracket 34 provided at its opposite end 95 with an eye 35. The casing 18 of the switch, as illustrated in connection with the preferred construction, is freely received through said eye and threaded upon the inner end portion of said casing to confront 100 opposite sides of the eye are nuts 36 securing the casing upon the bracket. The bracket is provided with relatively offset end portions and, as will be observed, is adapted to support the switch in such position that when the rod 33 is shifted rearwardly for moving the reverse gear of the 105 110

2
gear set to active position, said rod will engage the rod 21 of the switch plunger for closing the circuit in the manner previously explained. Otherwise, this modification of 5 the invention is identical with the preferred construction and further description is accordingly deemed unnecessary.

Having thus described the invention, what is claimed as new is:

- 10 In a device of the character described, the combination of an outer tubular switch casing, a tubular insulating plug closed at one end and removably engaged in one end of the casing closing the casing at said end 15 thereof, a switch member mounted upon the

closed end of said plug and housed within the lines thereof, a closure plug removably engaged in the opposite end of the casing, a plunger conforming to the internal diameter of the casing and slidable in said casing, the plunger being provided at one end with a reduced plunger rod projecting freely through the latter plug and at its opposite end with a reduced alined contact 20 rod to cooperate with said switch member, and a spring bearing between the inner end of said first mentioned plug and the plunger normally holding the plunger retracted.

In testimony whereof I affix my signature.

MARION C. WATERS. [L. s.]
